(57) **CLAIM**

The ornamental design for a folding hipper roller, as shown and described.

DESCRIPTION

FIG. 1 is a view of frontal isometric view of our folding hipper roller shown deployed;

FIG. 2 is a bottom isometric view thereof;

FIG. 3 is a front elevational view thereof;

FIG. 4 is an enlarged end elevational view thereof;

FIG. 5 is an enlarged elevational view of the opposite end;

FIG. 6 is a top plan view thereof;

FIG. 7 is a bottom plan view thereof;

FIG. 8 is a rear elevational view thereof;

FIG. 9 is a view of frontal isometric view of our folding hipper roller shown in a folded, transportation orientation;

FIG. 10 is a bottom isometric view of the folded hipper roller;

FIG. 11 is a front elevational view of the folded hipper roller;

FIG. 12 is an enlarged, end elevational view of the folded hipper roller;

FIG. 13 is an enlarged elevational view of the opposite end of the folded hipper roller;

FIG. 14 is a top view of the folded hipper roller;

FIG. 15 is a bottom plan view of the folded hipper roller; and,

FIG. 16 is a rear elevational view of the folded hipper roller.
